J. D. PEDERSEN.

FIREARM.

APPLICATION FILED DEC. 26, 1919.

1,391,499.

Patented Sept. 20, 1921.

FIG. 1.

Inventor:

John D. Pedersen

By his Atty, J. H. Richards.

UNITED STATES PATENT OFFICE.

JOHN D. PEDERSEN, OF JACKSON, WYOMING.

FIREARM.

1,391,499.

Specification of Letters Patent. Patented Sept. 20, 1921.

Original application filed July 30, 1915, Serial No. 42,774. Renewed July 17, 1919, Serial No. 311,689.
Divided and this application filed December 26, 1919. Serial No. 347,436.

To all whom it may concern:

Be it known that I, JOHN D. PEDERSEN, a citizen of the United States, residing in Jackson, in the county of Lincoln and State 5 of Wyoming, have invented certain new and useful Improvements in Firearms, of which the following is a specification.

This invention relates more especially to that class of firearms usually designated as 10 small arms, and a principal object of the invention is to furnish an improved grip-safety device particularly applicable to auto-loading and automatic pistols.

One class of small-arms to which my present improvements are applicable, includes the auto-loading pistols having a grip-stock, or handle portion of the frame or receiver of the fire-arm, which is adapted to receive a safety device operable by hand grip or 20 compression.

An improved auto-loading pistol of this kind is described in my Patent No. 1,348,733, dated August 3, 1920, and granted on my copending application (renewal) Serial No. 25 311,689, filed July 17, 1919, and the improvements herein described and claimed are also illustrated in my said patent but are not claimed therein. Therefore, for convenience of illustration, I have herein 30 shown my present improvements as arranged and applied to the particular kind of auto-loading pistol which is shown in the drawings of said patent, to which reference may be had.

The features of my present grip-safety device are that it is a grip or handle contained safety device, arranged to prevent firing of the firearms by locking the firing-member or hammer and the trigger-sear 40 when my device is in normal or safety position. Also, where the firearm is provided with a sliding breech-action comprising a firing-pin, to prevent discharge of the fire-arm by locking the breech-action to prevent 45 contact between the firing-pin and the cartridge, so that action of the firing-member or hammer on the firing-pin will not explode the cartridge, this feature being accomplished by a movable member or controller which in the present embodiment of 50 my invention is not provided with a means for guiding in its movement other than a pivotally operating arm.

Another feature is that means is provided 55 for coaction of the movable member or con-

troller and the trigger of the firearm, by which a second pull on the trigger, before the trigger is permitted to move forward after a first rearward pull, will not discharge the firearm, the trigger being normally in forward position and movable rearwardly by pull thereon.

In the accompanying drawings, which illustrate an embodiment of my grip-safety device,

Fig. 1, is a side elevation, partly broken away, of a pistol provided with my grip-safety-device.

Fig. 2, is a fragmentary side view, of my grip-safety device, on a larger scale than Fig. 1, partly broken away to show the parts of my grip-safety device.

Fig. 3, is a detail sectional view of my grip-safety device on the line 3—3 of Fig. 2.

Fig. 4, is a top or plan view of my grip-safety device on the line 4—4 of Fig. 2.

Similar reference characters refer to similar parts throughout the several views.

My grip safety device comprises a frame and a grip-safety member pivoted together 80 by a transverse journal pin, the frame carrying a spring, which is a hammer-actuating or main firing-spring reacting upon a pin-locking slidable member, whereby the said two members are held assembled and 85 said spring is held under compression, so that by sliding movement of said pin-lock the above-mentioned transverse journal-pin can be released and withdrawn, thereby releasing both said spring and the grip-safety 90 member.

The grip-safety member, designated by G', is hand compressible or yieldable and is shown pivoted to the frame or receiver B near the lower end of the handle-portion 95 or grip-stock thereof, Fig. 1, by means of a pivot pin g. The member G' closes the slot or space 2^a formed in the frame of the pistol to receive the grip-safety device denoted generally by G, and which slot or space is of use 100 in assembling the various parts of my device.

The grip-safety member G', is shown bored out at 7^a from below to receive the spring 8^e, Fig. 1. The spring plunger 8^c and the spring plug or abutment 7^b are 105 shown operatively connecting with the spring 8^e. The spring plug 7^b, the upper end of which receives the lower end of the spring 8^e, has an annular groove 7^e. The loose fitting pin g which pivots the grip-safety mem- 110

ber to the frame or receiver B may also have an annular groove, so that when the spring 8^e is compressed by moving the spring plug 7^b upwardly the grip-safety pin g may 5 be inserted to connect pivotally the grip-safety-member G' to the grip-stock of the frame or receiver B. On releasing the spring plug 7^b, the spring 8^e will move it downward until the top side of the annular 10 groove in the plug bears against the top of the pivot g in said groove thereof and thus holds said pin against being moved endwise.

To remove the grip-safety pin g, it is only necessary to push the spring plug 7^b upward, 15 to release this locking engagement. The cupped top 8^m of the spring plunger 8^e receives the lower end of the spring rod 8^b, the upper end of which is pivotally secured to the firing member or hammer H, the effect 20 of the spring being to throw or press the hammer H forwardly at all times. When the hammer is in its cocked position a line drawn through the pivot 8^a, which secures the spring rod 8^b, to the hammer H, and 25 through the grip-safety pin g, will pass in front of the center of the cupped or ball-and-socket engagement between the spring plunger 8^e and the spring rod 8^b. Hence the action of the spring 8^e tends to hold the 30 grip-safety member G' in its rear-most position when the hammer is cocked, and also holds one end, G², in contact or engagement with the adjacent portion of the frame of the fire-arm. All of which is more particu- 35 larly described in my said patent.

The top portion of the grip-safety member G' is slotted out at 7^d, Fig. 2, to furnish clearance for the hammer H and the sear S, leaving a pair of side walls 7^d which 40 are extended to provide a pair of locking prongs 7^t. These prongs or lever arms 7^t are located outside of, and clear of, the rear end of the trigger F, of the fire-arm, and when the grip-safety member is in its rear- 45 ward or safety position, these lever arms are immediately below the bottom-sides of the shoulder 14^p on the rockable member or controller N, which is thereby locked against downward movement, the purpose of the 50 rockable controller N, being to prevent or allow movement of the sliding breech-action of the fire-arm, the controller N being rockable upwardly and downwardly to accomplish this purpose.

55 The rockable member or controller N is provided with a spring operated actuating means or actuator 14^m, which engages a lever member n, pivotally attached to the rockable member or controller, and which en- 60 gages a lever-face 17^c of the sear S.

The rockable member or controller N, is rocked or moved in one direction, that is, upwardly, by movement of the hammer H from fired position to firing or cocked po- 65 sition, through engagement of the hammer

with the sear S, and engagement of the lever-face 17^c, of the sear S, with the lever member n, which in turn engages the actuator 14^m. The rockable member or controller N, is rocked in a reverse direction, 70 that is, downwardly, by movement of the hammer H from firing or cocked position to fired position, through movement of the sear S, by the hammer, the arms 17^t, of the sear S engaging or bearing down upon the upper 75 surfaces of the shoulder 14^p, of the controller N, and moving it downward.

The rockable member or controller N, is provided with an arm, or preferably with 80 forked arms 15, passing on each side of the hammer, and pivoted together by a pin or journal 16, which engages a recess, 17, shown in outline Fig. 2, in the hammer H, to allow the firing means or hammer H to assume a cocked or firing position without 85 interference with the rockable member or controller. The pin 16, is secured at its ends to the receiver or frame B, of the fire-arm and the rockable member or controller N, is thus supported and a guide-way for it 90 in its rocking motion is obviated.

A link 18, pivotally connects the rockable member or controller N, to the trigger member F, which is movable forwardly to normal firing position by means not shown, but 95 described and set forth in my said patent, and by pull thereon movable rearwardly to discharge the fire-arm. The purpose of said link is to control the movement of the trigger member F so that a second pull on the 100 trigger member will not discharge the fire-arm unless the trigger member is first permitted to move forward to its normal or forward position after a first pull thereon. Thus Fig. 2, the trigger member is shown 105 in normal or forward position, although the fire-arm is locked against discharge, the lower portion or end-face 6ⁿ of the trigger member adjacent to the means or recess 6^m for receiving the sear S, being in engagement with the ends 17^d of the sear S. Compression of the grip-safety member G', will release the rockable member N for movement downwardly to release the breech action, where the fire-arm is provided with 110 a breech action, and to release the sear member and hammer. Pull upon the trigger member F will move the sear member S to release the firing member or hammer H for movement to fired position. The rockable member or controller N, by means of the link 18, when moved downwardly will move the trigger member F downwardly so that the end of the trigger member F will be in the position shown in Fig. 1, the ends 17^d 115 of the sear S, then being receivable in the recess or receiving means 6^m of the trigger member and thus a second pull on the trigger F, without permitting the trigger to move forward to its normal position will act 120

125 130 135

on the sear S, but will not effect discharge of the firearm. In this feature of my invention, however, I do not restrict myself to the use of a rockable member or controller.

It will be noted that if the notch 8^j on the hammer H should give away or be accidentally chipped or broken and rendered ineffective, the hammer in flying forward would be arrested during this movement and before it struck the firing pin of the fire-arm, since the sear S, would not be allowed to yield and revolve away from the hammer H because of the engagement of the controller N with the sear S and the camming effect of the eccentric cam surfaces 8^k of the hammer engaging the adjacent surfaces of the sear S.

To release the hammer H to fire the arm the grip-safety member G' must be moved to its compressed or forward position prior to the pulling of the trigger member F to discharge the fire-arm. Such hand-grip pressure brings the locking arms 7^f on the grip-safety member forward from under the bottom-sides 14^e on the rockable member or controller N to the recess 14^r, and thus allows the sear S to be revolved to release the hammer H. When the hammer is so released the controller N will be moved downward by the operation of the hammer H and the sear member S, the grip-safety member G' being in its forward or compressed position. The rockable member or controller N is movable to upward or locking position by the actuator 14^m when the firing member or hammer is moved to cocked or firing position, the grip-safety member G' then being in rearward or non-compressed position. The grip-safety member G' therefore, is an indicator of the hammer position, in that the grip-safety member is always in its forward or unlocking position, when the hammer H is forward, or in fired position, and is in its rearward or locking position, when the hammer is cocked or in firing position, provided in the latter case, the grip-safety member is allowed by the user of the firearm to assume this rearward or locking position.

The described arrangement of the rockable member or controller N and the grip-operable safety member G' also affords means for holding the sliding breechaction of the firearm in forward position, when the firearm is provided with a sliding breechaction. To do this the controller N is movable upwardly so that the upper end or top 14^t, thereof projects into the path of the slide breechaction of the fire-arm and interferes with the rearward sliding movement thereof. If the grip-safety member G' is released it will then lock the rockable member or controller N in such upward or interfering position so that the slide

breechaction of the firearm will be held in its forward position. To allow the slide breechaction of the fire-arm to go to rearward position it is only necessary to compress the grip-safety member G'—without 70 however requiring the trigger member F to be pulled—to permit movement of the rockable member or controller N downwardly out of such interfering position, and thereby permit the slide breechaction of the fire-arm to move to its rearward position. 75

The slide hammer spring or firing spring plug 7^b, when my grip-safety device is assembled in the firearm, projects below the bottom line of the butt of the fire-arm, in this case a pistol, at or near the rear edge of the butt, so that by taking the fire-arm in hand and bearing it down upon a table or other plane surface, the plug 7^b may be slid or moved inwardly in the butt far enough to permit the removal of the pivot g, which is freely-fitted in the frame or receiver B, thus enabling the mechanism to be disassembled without the use of tools, other than a suitably stout pin or slender nail to push out the various journal pins of the firing-train mechanism of the fire-arm. 85 90

Having thus described my invention, I claim:

1. In a firearm, in combination, a frame of said firearm, a firing member movable to firing position and to fired position, sear means engageable with said firing member, rockable means, means for moving said rockable means in direction to lock said sear means and firing member in firing position, means for moving said rockable means in direction reverse to the first mentioned direction when said firing member is moved to fired position, grip-compressible means engageable with said frame and with said rockable means when in position of safety, to block said rockable means in said locking position, and releasable from both said engagements by grip-compression, means for moving said firing member to fired position, trigger means normally in forward position and by pull thereon movable rearwardly, when said grip-compressible means is grip-compressed, to move said sear means for releasing said firing member for movement to fired position, and means for preventing, after a first pull on said trigger means, movement of said sear means by a second pull on said trigger means before movement of said trigger means to said normal forward position. 115

2. In a firearm, in combination, a frame of said firearm, a sliding breechaction, a firing member movable to firing position and to fired position, sear means engageable with said firing member, rockable means engageable with said sear means, means for moving said rockable means in direction to lock said 125 130

- sliding breechaction and lock said sear means and firing member in firing position, means for moving said rockable means in direction reverse to the first-mentioned direction when 5 said firing member is moved to fired position, grip-compressible means engageable with said frame and engageable with said rockable means when in position of safety, to block said rockable means in said locking to block said rockable means in said locking 10 position, and releasable from both said engagements by grip-compression, means for moving said firing member to fired position, trigger means normally in forward position and by pull thereon movable rearwardly, when said grip-compressible means is grip-compressed, to move said 15 sear means for releasing said firing member for movement to fired position, and means comprising means operatively connecting said rockable means and said trigger means for preventing, after a first pull on said trigger means, movement of said sear means by 20 a second pull on said trigger means before movement of said trigger means to said normal forward position.
3. In a firearm, in combination, a frame 25 of said firearm, a firing member movable to firing position, and to fired position, sear means engageable with said firing member, rockable means, means for moving said rockable means in direction to lock said sear 30 means and firing member in firing position, means for moving said rockable means in direction reverse to the first mentioned direction when said firing member is moved to fired position, grip-compressible means engageable with said frame and with said rockable means when in said locking position, and releasable from both said engagements by grip-compression, means for moving said firing member to fired position, trigger 35 means normally in forward position and by pull thereon movable rearwardly, when said grip-compressible means is grip-compressed, to move said sear means for releasing said firing member for movement to fired position, trigger means normally in forward position and by pull thereon movable rearwardly, when said grip-compressible means is grip-compressed, to move said sear means for releasing said firing member for movement to fired position, and means comprising link means operatively 40 connected to said rockable means and to said trigger means for preventing, after a first pull on said trigger means, movement of said sear means by a second pull on said trigger 45 means normally in forward position and by pull thereon movable rearwardly, when said grip-compressible means is grip-compressed, to move said sear means for releasing said firing member for movement to fired position, and means comprising means operatively connecting said rockable means and trigger means for preventing, after a first pull on said trigger means, movement of said sear means by a second pull on said trigger 50 means before movement of said trigger means to said normal forward position.
4. In a firearm, in combination, a frame of said firearm, a sliding breechaction, a firing member movable to firing position and to fired position, sear means engageable with said firing member, rockable means engageable with said sliding breechaction, means for moving said rockable means in direction to lock said sliding breechaction and lock 55 said sear means and firing member in firing position, means for moving said rockable means in direction reverse to the first-mentioned direction when said firing member is moved to fired position, grip-compressible means engageable with said frame and with 60 said rockable means to block the rockable means in said locking position, and releas- 65
- said rockable means when in position of safety, to block said rockable means in said locking position, and releasable from both said engagements by grip-compression, means for moving said firing member to fired position, trigger means normally in forward position and by pull thereon movable rearwardly, when said grip-compressible means is grip-compressed, to move said sear means for releasing said firing member for movement to fired position, and means comprising means operatively connecting said rockable means and said trigger means for preventing, after a first pull on said trigger means, movement of said sear means by a second pull on said trigger means before movement of said trigger means to said normal forward position.
5. In a firearm, in combination, a frame of said firearm, a firing member movable to firing position and to fired position, sear means engageable with said firing member, rockable means, means for moving said rockable means in direction to lock said sear means and firing member in firing position, means for moving said rockable means in direction reverse to the first-mentioned direction when said firing member is moved to fired position, grip-compressible means engageable with said frame and engageable with said rockable means when in position of safety, to block said rockable means in said locking position, and releasable from both said engagements by grip-compression, means for moving said firing member to fired position, trigger means normally in forward position and by pull thereon movable rearwardly, when said grip-compressible means is grip-compressed, to move said sear means for releasing said firing member for movement to fired position, and means comprising link means operatively connected to said rockable means and to said trigger means for preventing, after a first pull on said trigger means, movement of said sear means by a second pull on said trigger means before movement of said trigger means to said normal forward position.
6. In a firearm, in combination, a frame of said firearm, a sliding breechaction, a firing member movable to firing position and to fired position, rockable means engageable with said sliding breechaction, sear means engageable with said firing member and with said rockable means, means for moving said rockable means to lock said sliding breechaction, and lock said sear means and firing member in firing position, means for moving said rockable means to unlock position when said firing member is moved to fired position, grip-compressible means engageable with said frame and with said rockable means to block the rockable means in said locking position, and releas-

able from both said engagements by grip-compression, means for moving said firing member to fired position, trigger means normally in forward position and by pull thereon 5 movable rearwardly, when said grip-compressible means is grip-compressed, to move said sear means for releasing said firing member for movement to fired position, and means comprising link means 10 operatively connected to said rockable means and to said trigger means for preventing, after a first pull on said trigger means, movement of said sear means by a second pull on said trigger means before movement of said trigger 15 means to said normal forward position.

7. In a firearm, in combination, a frame of said firearm, a firing member movable to firing position and to fired position, a rockable member, a sear member engageable 20 with said firing member and engageable with said rockable member, means for moving said rockable member in direction to lock said sear member and firing member in firing position, said rockable member being 25 movable in direction reverse to the first-mentioned direction by said sear member when said firing member is moved to fired position, a grip-operable member engageable with said frame and with said rockable 30 member when in position of safety, to block said rockable member in said locking position, and releasable from both said engagements by grip-compression, spring means for moving said firing member to fired position, and affording grip-compression of the grip-operable member, and for returning the grip-operable member to engagement with said frame after grip-compression, a trigger member normally in forward 35 position.

35. In a firearm, in combination, a frame of said firearm comprising a grip-stock, a firing member movable to firing position and to fired position, and provided with a cock-notch and a cam face, a controller having an arm pivotally supported by said frame, said controller being provided with an actuator, a lever member carried by said controller provided with a face engaging said actuator and provided with an extending end, a sear member engageable with said controller provided with a locking shoulder for engaging said cock-notch and a face for engaging said cam face of the firing member, and provided with a lever-face engaging said extending end of the lever member, and provided with projecting lower ends, said controller being movable upwardly by said actuator to lock said sear member and firing member in firing position, and being movable downwardly by said sear member when said firing member is moved to fired position, a grip-operable member pivotally attached to said grip-stock and engageable with said frame and engageable with said controller to block the controller in said locking position, and releasable from both said engagements by grip-compression, spring means for moving said firing member to fired position, and affording grip-compression of the grip-operable member, and for returning the grip-operable member to engagement with said frame after grip-compression, a trigger member normally in forward position and by pull thereon movable rearwardly, when said grip-operable member is grip-compressed, to move said sear member for releasing said firing member for movement to fired position, and means comprising link means pivotally connected to said rockable member and pivotally connected to said trigger member for preventing, after a first pull on said trigger member, movement of said sear member by a second pull on said trigger member before movement of said trigger member to said normal forward position.

8. In a firearm, in combination, a frame of said firearm, a sliding breechaction, a firing member movable to firing position and to fired position, a rockable member engageable with said sliding breechaction, a sear member engageable with said firing member and engageable with said rockable member, means for moving said rockable member in direction to lock said sliding breechaction, and lock said sear member and firing member in firing position, said rockable member being movable in direction reverse to the first-mentioned direction by said sear mem-

ber when said firing member is moved to fired position, a grip-operable member engageable with said frame and with said rockable member when in position of safety, to block said rockable member in said locking position, and releasable from both said engagements by grip-compression, spring means for moving said firing member to fired position, and affording grip-compression of the grip-operable member, and for returning the grip-operable member to engagement with said frame after grip-compression, a trigger member normally in forward position and by pull thereon movable rearwardly, when said grip-operable member is grip-compressed, to move said sear member for releasing said firing member for movement to fired position, and means comprising a link pivotally connected to said rockable member and pivotally connected to said trigger member for preventing, after a first pull on said trigger member, movement of said sear member by a second pull on said trigger member before movement of said trigger member to said normal forward position.

9. In a firearm, in combination, a frame of said firearm comprising a grip-stock, a firing member movable to firing position and to fired position, and provided with a cock-notch and a cam face, a controller having an arm pivotally supported by said frame, said controller being provided with an actuator, a lever member carried by said controller provided with a face engaging said actuator and provided with an extending end, a sear member engageable with said controller provided with a locking shoulder for engaging said cock-notch and a face for engaging said cam face of the firing member, and provided with a lever-face engaging said extending end of the lever member, and provided with projecting lower ends, said controller being movable upwardly by said actuator to lock said sear member and firing member in firing position, and being movable downwardly by said sear member when said firing member is moved to fired position, a grip-operable member pivotally attached to said grip-stock and engageable with said frame and engageable with said controller to block the controller in said locking position, and releasable from both said engagements by grip-compression, spring means for moving said firing member to fired position, and affording grip-compression of the grip-operable member, and for returning the grip-operable member to engagement with said frame after grip-compression, a trigger member normally in forward position provided with a rear end having a projection and an adjacent recess, said trigger member being movable rearwardly by pull thereon to move said sear member when said grip-operable mem-

ber is grip-compressed, and a link pivotally attached to said controller and pivotally attached to said trigger member for moving the trigger member to position for engaging 5 said projecting lower ends thereof with said projecting lower ends of the sear member when said controller is in upward position, and for moving the trigger member to position for receiving in said recess said projecting lower ends of the sear member when 10 said controller is in downward position.

10. In a firearm, in combination, a frame of said firearm comprising a grip-stock, a sliding breechaction, a firing member movable to firing position and to fired position, and provided with a cock-notch and a cam face, a controller provided with an arm pivotally supported by said frame, said controller being provided with an actuator, a 15 lever member carried by said controller, provided with a face engaging said actuator, and provided with an extending end, a sear member engageable with said controller provided with a locking-shoulder for engaging 20 said cock-notch and a face for engaging said cam face of the firing member, and provided with a lever face engaging said extending end of the lever member, and provided with projecting lower ends, said controller being 25 movable upwardly by said actuator to lock said sear member and firing hammer in firing position, and being movable downwardly by engagement of said ends of the arm of the sear member with said upper surfaces of the shoulder of the controller when said firing member is moved to fired position, a grip- 30 safety member pivotally attached at one end thereof to said grip-stock and engageable at the other end thereof with said frame, provided with locking prongs for engaging 35 said bottom-sides of said controller to block the controller in said locking position, and releasable from both said engagements by grip-compression, spring means for moving 40 said firing hammer to fired position, and affording grip-compression of the grip-safety member, and for returning the grip-safety member to engagement with said frame after grip-compression, a trigger member normally in forward position, provided with a rear end having a projection 45 and an adjacent recess, said trigger member being movable rearwardly by pull thereon to move said sear member when said grip-safety member is grip-compressed, and a link pivotally attached to said controller and 50 said trigger member for moving the trigger member to position for engaging said projecting end thereof with said projecting lower ends of the sear member when said controller is in said upward position, and for moving 55 the trigger member to position for receiving in said recess said projecting lower ends of the sear member when said controller is in downward position.

11. In a firearm, in combination, a frame of said firearm comprising a grip-stock, a firing hammer movable to firing position and

to fired position, and provided with a cock-notch and an eccentric cam-face, a controller having an arm pivotally supported by said frame, said controller being provided with an actuator, and provided with a shoulder having upper surfaces and having bottom-sides, a lever member pivotally attached to said controller, provided with a face engaging said actuator and provided with an extending end, a sear member provided with a locking shoulder for engaging said cock-notch and a face for engaging said eccentric cam-face of the firing hammer, and provided with an arm having ends for engaging 65 said upper surfaces of the shoulder of the controller, and provided with a lever-face engaging said extending end of the lever-member, and provided with projecting lower ends, said controller being movable upwardly by said actuator to lock said sear member and firing hammer in firing position, and being movable downwardly by engagement of said ends of the arm of the sear member with said upper surfaces of the shoulder of the controller when said firing member is moved to fired position, a grip- 80 safety member pivotally attached at one end thereof to said grip-stock and engageable at the other end thereof with said frame, provided with locking prongs for engaging 85 said bottom-sides of said controller to block the controller in said locking position, and releasable from both said engagements by grip-compression, spring means for moving 90 said firing hammer to fired position, and affording grip-compression of the grip-safety member, and for returning the grip-safety member to engagement with said frame after grip-compression, a trigger member normally in forward position, provided with a rear end having a projection 95 and an adjacent recess, said trigger member being movable rearwardly by pull thereon to move said sear member when said grip-safety member is grip-compressed, and a link pivotally attached to said controller and 100 said trigger member for moving the trigger member to position for engaging said projecting end thereof with said projecting lower ends of the sear member when said controller is in said upward position, and for moving 105 the trigger member to position for receiving in said recess said projecting lower ends of the sear member when said controller is in downward position.

12. In a firearm, in combination, a frame 11 of said firearm, comprising a grip-stock, a sliding breech-action, a firing hammer movable to firing position and to fired position, and provided with a cock-notch and an eccentric cam face, a controller having an arm 12 pivotally supported by said frame, said controller being provided with means for engaging said sliding breechaction, and pro-

- vided with an actuator, and provided with a shoulder having upper surfaces and having bottom sides, a lever member pivotally attached to said controller provided with a 5 face engaging said actuator and provided with an extending end, a sear member provided with a locking shoulder for engaging said cock-notch and a face for engaging said eccentric cam-face of the firing hammer, and
- 10 provided with an arm having ends for engaging said upper surfaces of the shoulder of the controller, and provided with projecting lower ends, said controller being movable upwardly by said actuator to lock 15 said sliding breechaction, and lock said sear member and firing hammer in firing position, and being movable downwardly by engagement of said ends of the arm of the sear member with said upper surfaces of the 20 shoulder of the controller when said firing hammer is moved to fired position, a grip-safety member pivotally attached at one end thereof to said grip-stock and engageable at the other end thereof with said frame, provided with locking prongs for engaging said 25 bottom-sides of the controller to block the controller in said locking position, and releasable from both said engagements by grip-compression, spring means for moving 30 said firing hammer to fired position, and affording grip-compression of the grip-safety member and for returning the grip-safety member to engagement with said frame after grip-compression, a trigger member 35 normally in forward position, provided with a rear end having a projection and an adjacent recess, said trigger member being movable rearwardly by pull thereon to move said sear member when said grip-safety member 40 is grip-compressed, and a link pivotally attached to said controller and pivotally attached to said trigger member for moving the trigger member to position for engaging said projecting end thereof with said projecting lower ends of the sear member when said 45 controller is in downward position.
13. In a firearm, in combination, a firing member movable to firing position and to fired position, sear means engageable with said firing member, a rockable controller for locking said sear means and firing member when said firing member is moved to firing position, said controller being rockably movable to unlocking position when said firing member is moved to fired position, trigger means normally in forward position and by pull thereon movable rearwardly to move said sear means for 50 releasing said firing member for movement to fired position, and means operatively connecting said rockable means and said trigger means for preventing, after a first pull on said trigger means, movement of said sear means by a second pull on said trigger means before movement of said trigger means to said normal forward position.
14. In a firearm, in combination, a sliding breechaction, a firing member movable to firing position and to fired position, sear means engageable with said firing member, a rockable controller for locking said sliding breechaction, and locking said sear means and firing member when said firing member is moved to firing position, said controller being rockably movable to unlocking position when said firing member is moved to fired position, trigger means normally in forward position and by pull thereon movable rearwardly to move said sear means for releasing said firing member for movement to fired position, and means for preventing, after a first pull on said trigger means, movement of said sear means by a second pull on said trigger means before movement of said trigger means to said normal forward position.
15. In a firearm, in combination, a firing member movable to firing position and to fired position, sear means engageable with said firing member, a rockable controller for locking said sear means and firing member when said firing member is moved to firing position, said controller being rockably movable to unlocking position when said firing member is moved to fired position, trigger means normally in forward position and by pull thereon movable rearwardly to move said sear means for releasing said firing member for movement to fired position, and means operatively connecting said rockable means and said trigger means for preventing, after a first pull on said trigger means, movement of said sear means by a second pull on said trigger means before movement of said trigger means to said normal forward position.
16. In a firearm, in combination, a sliding breechaction, a firing member movable to firing position and to fired position, sear means engageable with said firing member, a rockable controller for locking said sear means and firing member when said firing member is moved to firing position, said controller being rockably movable to unlocking position when said firing member is moved to fired position, trigger means normally in forward position and by pull thereon movable rearwardly to move said sear means for releasing said firing member for movement to fired position, and means operatively connecting said rockable means and said trigger means for preventing, after a first pull on said trigger means, movement of said sear means by a second pull on said trigger means before movement of said trigger means to said normal forward position.

17. In a firearm, in combination, a firing member movable to firing position and to fired position, sear means engageable with said firing member, a controller provided with a pivoted arm for supporting the controller, said controller being movable to lock said sear means and firing member when the firing member is moved to firing position, and movable to unlocking position when said firing member is moved to fired position, trigger means normally in forward position, and by pull thereon movable rearwardly to move said rear means for releasing said firing member for movement to fired position, and link means operatively connecting said controller and said trigger means for preventing, after a first pull on said trigger means, movement of said sear means by a second pull on said trigger means before movement of said trigger means to said normal forward position.
18. In a firearm, in combination, a frame of said firearm, a sliding breechaction, a firing member movable to firing position and to fired position, sear means engageable with said firing member, a controller provided with a pivoted arm for supporting the controller, said controller being movable to lock said sliding breechaction, and lock said sear means and firing member when the firing member is moved to firing position, and movable to unlocking position when said firing member is moved to fired position, trigger means normally in forward position, and by pull thereon movable rearwardly to move said sear means for releasing said firing member for movement to fired position, and link means operatively connecting said controller and said trigger means for preventing, after a first pull on said trigger means, movement of said sear means by a second pull on said trigger means before movement of said trigger means to said normal forward position.
19. In a firearm, in combination, a sliding breechaction, a firing member movable to firing position and to fired position, sear means engageable with said firing member, a controller provided with a pivotally supported arm, said controller being engageable with said sliding breechaction, and movable in a direction to lock said sliding breechaction, and lock said sear means and firing member in firing position, and movable in a reverse direction when said firing member is moved to fired position, trigger means normally in forward position and by pull thereon movable rearwardly to move said sear means for releasing said firing member for movement to fired position, and means comprising means operatively connecting said controller and said trigger means for preventing, after a first pull on said trigger means, movement of said sear means by a second pull on said trigger means before movement of said trigger means to said normal forward position.
20. In a firearm, in combination, a firing member movable to firing position and to fired position, a sear member engageable with said firing member and provided with projecting lower ends, a controller rockably movable upwardly to lock said sear member and firing member in firing position, and rockably movable downwardly to unlocking position by the sear member when said firing member is moved to fired position, a trigger member normally in forward position and provided with a rear end having a projection and an adjacent recess, said trigger member being movable rearwardly by pull thereon to move said sear member for releasing said firing member for movement to fired position, and a link operatively connecting said controller and said trigger member for moving the trigger member to position for engaging said projecting end thereof with said projecting lower ends of the sear member when said controller is in upward position, and for moving the trigger member to position for receiving in said recess said projecting lower ends of the sear member when said controller is in downward position.
21. In a firearm, in combination, a sliding breechaction, a firing member movable to firing position, and to fired position, a sear member engageable with said firing member and provided with projecting lower ends, a controller engageable with said sliding breechaction, said controller being rockably movable upwardly to lock said sliding breechaction, and lock said sear member and firing member in firing position, and rockably movable downwardly to unlocking position by the sear member when said firing member is moved to fired position, a trigger member normally in forward position and provided with a rear end having a projection and an adjacent recess, said trigger member being movable rearwardly by pull thereon to move said sear member for releasing said firing member for movement to fired position, and a link operatively connecting said controller and said trigger member for moving the trigger member to position for engaging said projecting end thereof with said projecting lower ends of the sear member when said controller is in upward position, and for moving the trigger member to position for receiving in said recess said projecting lower ends of the sear member when said controller is in downward position.
22. In a firearm, in combination, a firing member movable to firing position and to fired position, a sear member engageable with said firing member and provided with projecting lower ends, a controller provided with a pivoted supporting and guiding arm, said controller being movable upwardly to

lock said sear member and firing member when the firing member is moved to firing position, and movable downwardly to unlocking position by the sear member when 5 said firing member is moved to fired position, a trigger member normally in forward position and provided with a rear end having a projection and an adjacent recess, said trigger member being movable rearwardly 10 by pull thereon to move said sear member for releasing said firing member for movement to fired position, and a link operatively connecting said controller and said trigger member for moving the trigger member to position 15 for engaging said projecting end thereof with said projecting lower ends of the sear member when said controller is in upward position, and for moving the trigger member to position for receiving in said recess said projecting lower ends of the sear member when 20 said controller is in downward position.

23. In a firearm, in combination, a sliding breechaction, a firing member movable to firing position and to fired position, a sear member engageable with the firing member and provided with projecting lower ends, a controller provided with a pivoted supporting and guiding arm, said controller being

engageable with said sliding breechaction, 30 and movable upwardly to lock said sliding breechaction and lock said sear member and firing member when the firing member is moved to firing position, and movable downwardly to unlocking position by the sear 35 member when said firing member is moved to fired position, a trigger member normally in forward position and provided with a rear end having a projection, and an adjacent recess, said trigger member being 40 movable rearwardly by pull thereon to move said sear member for releasing said firing member for movement to fired position, and a link operatively connecting said controller and said trigger member for moving the 45 trigger member to position for engaging said projecting end thereof with said projecting lower ends of the sear member when said controller is in upward position, and for moving the trigger member to position 50 for receiving in said recess said projecting lower ends of the sear member when said controller is in downward position.

JOHN D. PEDERSEN.
